UNITED STATES PATENT OFFICE.

ELWOOD B. AYRES, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

DRIER.

1,147,593.

Specification of Letters Patent.

Patented July 20, 1915.

Application filed August 3, 1914. Serial No. 354,839.

To all whom it may concern:

Be it known that I, ELWOOD B. AYRES, a citizen of the United States, residing in Philadelphia, Pennsylvania, have invented 5 certain Improvements in Driers, of which the following is a specification.

One object of this invention is to construct a drier in such a manner that two independent drying chambers can be located, one on 10 each side of a central circulating and heating chamber.

A further object of the invention is to so construct a drier having longitudinal heating and circulating chambers that the material being dried can be examined during 15 the drying operation.

A still further object of the invention is to reduce the height of the driers of this type.

This invention is particularly adapted for 20 drying plastic materials, such as drain pipes, bricks, &c., but it will be understood that it can be used for drying other materials as well.

In the accompanying drawings: Figure 1 25 is a plan view of my improved drier; Fig. 2 is a side view; and Fig. 3 is a transverse sectional view.

Referring to the drawings, 1 is the casing 30 having three longitudinal compartments 2, 2 and 3. The compartments 2, 2 are on each side of the central compartment 3 and in these side compartments are tracks upon which the trucks 4 are traversed through the drier. Located in the central chamber 3 is 35 a series of heating pipes 5 and above these pipes are the circulating fans 6 for causing the hot air to circulate in the manner indicated by the arrows. The fans are preferably driven as illustrated in the drawings. 40 Extending under the drying chambers 2, 2 are endless chains 7 having projections which engage an axle of each truck. These chains pass around wheels 8 so that, on turning the wheels, the several trucks can be 45 moved a predetermined distance.

In order to divide the heating chambers 2 into independent sections, I provide metallic curtains 9, which are adapted to rollers and these rollers are geared to a longitudinal 50 operating shaft 10 in the present instance, which can be turned either by hand or by

power. I preferably provide curtains at each end of the drier. Each curtain may be independently rolled either by hand or by power.

When it is desired to shift the trucks, the curtains are raised and after the trucks are shifted the curtains are again lowered, dividing the chamber into independent sections so that the material can be more thoroughly dried. The curtains also prevent the moist air of one section from entering another section.

Each section may be provided with vents to allow for the escape of moist air, and at 65 the side of the drier is a series of openings closed by doors having windows through which the material can be inspected as it is traversed through the drier.

While I have shown trucks to convey the 70 material through the drier other carriers may be substituted for the trucks if found desirable in carrying certain materials.

I claim:

1. The combination in a drier, of a casing 75 having three longitudinal chambers, the two side chambers being drying chambers for the material; means in said chambers for conveying said material; the central chamber having a series of heating pipes therein 80 and overhead rotating fans for causing the circulation of the air through the three chambers; and movable, transverse partitions located in the drying chambers for limiting the circulation of air, yet allowing 85 for the free movement of the conveying means when the material to be dried is shifted.

2. The combination in a drier, of a longitudinal heating chamber and a drying chamber; means in the heating chamber for heating 90 the air; a conveyer in the drying chamber; a series of transversely arranged curtains spaced a certain distance apart and acting as partitions to divide the drying 95 chamber into compartments; and curtains at each end of the drier forming doors; and means for simultaneously raising or lowering said curtains.

3. The combination in a drier, of a casing 100 having three longitudinal chambers therein, the central chamber being the heating cham-

ber and the side chambers being the drying chambers; circulating fans in the heating chambers; a series of transversely arranged curtains, spaced a given distance apart, arranged to separate the casing into a series of compartments; and means for raising and lowering the curtains in unison.

In testimony whereof, I have signed my name to this specification, in the presence of two subscribing witnesses.

ELWOOD B. AYRES.
